HOUSING FOR A RADIO TUNER OR SIMILAR ARTICLE

Gerald J. Golden, 11143 Montana, Los Angeles, Calif.
90049; James E. Walker, 2102 W. 157th St., Gardena,
Calif. 90249; and Tom T. Tsuji, 2307 E. 2nd St., Los
Angeles, Calif. 90033

Filed Apr. 17, 1967, Ser. No. 6,727

Term of patent 14 years

(Cl. D56—4)

FIG. 1

FIG. 4

FIG. 5

FIG. 2

FIG. 3

FIGURE 1 is a perspective top view of a housing for a radio tuner or similar article, showing our new design; FIGURE 2 is a bottom view thereof;

FIGURE 3 is an inverted front elevational view thereof;

FIGURE 4 is a rear elevational view thereof; and

FIGURE 5 is a side elevational view thereof, taken along line 5—5 of FIGURE 2.

We claim:

The ornamental design for a housing for a radio tuner or similar article, as shown.
